UNITED STATES PATENT OFFICE

GEORGE E. FICHTNER, OF MORRIS COUNTY, AND MALCOLM G. VAN ARSDALE, OF ESSEX COUNTY, NEW JERSEY, ASSIGNORS TO VAN RAALTE COMPANY, INC., OF NEW YORK, N. Y., A CORPORATION OF NEW YORK

HOSIERY

Application filed January 15, 1930. Serial No. 420,859.

This invention relates to hosiery and, particularly, to stockings and socks.

Among the objects of this invention is to provide a stocking particularly designed to afford comfort to the wearer in the vicinity of the toe. It is common practice to make certain portions of a stocking of heavier material than the major portion of the stocking in order to provide greater wearing quality where the wear upon the stocking is severest. The toe is one of the portions of a stocking which is generally considered to require reinforcement and, according'y, the majority of stockings, if not all, are there 10 reinforced because of public demand. Compromises have heretofore been followed which incurred a sacrifice of fitting qualities in favor of convenience in manufacturing processes. This has resulted in the production 20 of a stocking which does not fit perfectly partly because the stocking commonly produced has a quickly tapering toe quite dissimilar to the broad shape of the forward portion of the foot. In the common form 25 of stocking there is a "bunching" of the material of the stocking at the toe which frequently causes a poor fit and discomfiture within the shoe. If the stocking fits the foot in such a manner that the toes-enveloping 30 sheath is completely filled, the reinforced material of the stocking exerts compression on the toes.

In the case of a stout foot the compression may be quite sensible, and even as to a stocking 35 of apparently comfortable fit there is a certain, though not always apparent, discomfiture because of the relative difference of the weight and elasticity of the materials covering different though adjacent portions 40 of the foot. It is therefore, among the objects of our invention to overcome the disadvantages outlined and to provide a stocking having a reinforced toe-portion which is easily conformable to the form of the 45 foot without oppression to the freedom and comfort of the toes.

Another object of the invention is to provide a stocking which, for the same length of foot, is suitable to comfortably clothe a 50 stout and fat foot as well as a bony foot of

the same length so that a person having a stout foot may not be required to purchase a larger size of stocking than necessary in order to secure a stocking having sufficient material to be taken into the breadth of the 55 stocking.

Another object of the invention is to provide a stocking having a wear-resisting toe portion which has provision at the outer sides of the foot for reducing friction—and 60 hence enhancing comfort—because of a poor fit and/or recurring spreading and movement of the foot within a shoe while walking, without in the least detracting from the wear resisting quality of the reinforced toe. 65

Other objects and advantages of the invention, some of which are related to and others of which are independent of the foregoing objects will be referred to in the description of the invention and in the claims. 70

In the drawings, Fig. 1 is a general view of the foot of a stocking embodying the invention.

Fig. 2 is a plan of the toe of the stocking.

Fig. 3 is a detail of an area of meshes.

Having reference to the drawings, 10 is a full fashioned stocking or sock of any type, which is provided with reinforcing portions at the heel 11 and the toe 12. While the reinforced portions may be made in divers 80 ways, one customary procedure involves the increasing in the number of wales per unit of width as compared with the number of wales in the stocking proper. In all reinforcements the quantity of thread and of material per unit area is necessarily increased, and, obviously, the portion of the stocking which is designed for wear-resisting is more harsh, less pliant and less elastic than the remaining body of the stocking. In fact the 85 elasticity is so limited that the toes-enveloping sheath of any particular stocking, is suitable, in dimensions, to accommodate only but a small range of sizes of toes. 90

The result is that a stout foot may be compressed—and increasingly compressed when within a shoe bearing weight—with attendant discomfiture. If a larger size of stocking, one having greater length of foot, is used then the wearer runs the risk of acquiring troubles 100

incident to too large sizes—blistered and tender feet because of folds and poor fit.

It is unquestionably better that all feet of the same length be capable of wearing the same size of stocking and in order to achieve this desideratum and attain the objects primarily stated, we provide along the sides of the toes-enveloping portion and where the wear and contact pressure between the foot and the shoe is greatest, open-work meshes formed of lace stitches and narrowings. These open-work meshes at 13 and 14 may best be formed in the manufacture of the stocking by omitting narrowing needles in the narrowing needles finger which forms the gusset in the toe of the stocking. The spacing of the meshes may be controlled by the number of needles omitted. The spacing of the meshes and the size of each area of meshes are factors which determine the degree of elasticity and expansibility to be had and we have found that the relative sizes of the areas, as illustrated, is admirably suited for the purposes of the invention. Such proportion of areas of meshes will give a good fit without tightness and they permit the toes to "breathe". The meshes formed of lace stitches and narrowings create elastic areas which are more expansible, both longitudinally of the foot and laterally, than the adjacent reinforcing areas with the result that good fitting of any foot may be had and, for a stout foot particularly, the expansibility lacking in the reinforcing of the toe is counteracted by the character of and the supply of material constituting the areas of meshes.

The bunching of material at the toe which frequently is present in stockings made by commonly used processes is obviated by the stocking of our invention for the meshes readily give in the direction of the broadest dimension across the base of the toes and the bunching which would otherwise exist at the end of the toes is taken up in the fore-shortening of the longitudinal dimensions of the mesh areas as the lateral dimensions of the mesh areas are expanded. As a consequence the toes-enveloping sheath neatly encases the toes without wrinkling or overlapping of material.

The meshes also provide more comfort, not only because of improved fitting qualities but because of the cushioning effect afforded thereby for the outer toes against the shoe. In the part of the shoe contacting the toes friction is high because of the recurring movement of the toes during walking and because of the closeness of fit of shoes, particularly women's shoes, with the result that soreness is often caused. The meshes provided are pliant, relatively soft and self-conforming and, therefore, eliminate irritation that might otherwise appear due to relatively harsher reinforcing material. While possessing physical attributes of the nature out-

lined, the areas of meshes have such structures as to wear well and prevent runs from starting at their locations, which locations are usually considered vulnerable for failures of that character. Then, again, the meshes provide for ventilation which is desirable for any clothed area subject to friction and movement.

The exact placing and sizes of the areas of meshes are not important except they should cover areas suitable for cushioning the outer toes, but they must be of such a character as to afford requisite elasticity. It is preferable that the areas of meshes be placed in balanced positions, as shown in Fig. 2. In such positions they are useful in assisting to correctly place the stocking on the foot so that the bottom seam, if any, will be in the middle of the foot and the rear seam will be started upwardly from the middle of the heel. The results attained and the advantages which have been related are most desirable and are either directly or indirectly attributable to the meshes formed of lace stitches and narrowings, but it is appreciated that meshes may be used which are formed in other ways, and which possess the features characterizing this invention, and that such meshes are intended to come within the scope of the invention as expressed in the claims.

What we claim is:

1. A full fashioned stocking having a reinforced toes-enveloping sheath and a pair of areas of openwork meshes constituting areas of fabric more elastic than the adjacent fabric of the sheath, there being one area of meshes on each side of the stocking within the reinforced toes-enveloping sheath, each area of meshes having a longitudinal dimension in the direction of extension of the toes and its narrowest dimension so disposed as to be expandable crosswise of the foot, whereby when the foot is placed within the stocking the mesh areas are expanded laterally and surplus material at the end of the toes is drawn in by the foreshortening of the longitudinal dimensions of the areas of meshes.

2. A full fashioned stocking having a reinforced toes-enveloping sheath, comprising a surface of closely knit reinforcing material extending across the top of the sheath and similar material extending across the under surface of the sheath, and areas of openwork meshes separating said surfaces at opposite edges and joined thereto, one on each side of the sheath between the upper and under surfaces and forming a part of the sheath, each of said areas of meshes being bounded by the fashioning marks which outline the diamond point of the stocking.

3. A full fashioned stocking having a reinforced toes-enveloping sheath or pocket including areas of openwork, each of said areas of openwork consisting of the area formed within the lines of narrowing or fashioning

marks as formed in the narrowing operation.

4. A full fashioned stocking comprising a reinforced toes-enveloping sheath or pocket and gussets or diamond points having their areas interspersed with openwork meshes which are formed in the narrowing operation by the narrowing needles.

5. A full fashioned stocking comprising a reinforced toes-enveloping sheath or pocket having therein areas of openwork meshes adapted to lie adjacent the outer toes, each of said areas of meshes consisting of at least two adjacent longitudinal rows of meshes which extend a substantial distance in the general direction of extension of the toes and are more elastic than the adjacent fabric of the toes-enveloping sheath or pocket.

In testimony whereof we hereto affix our signatures.
